UNITED STATES PATENT OFFICE.

HARRY W. SMITH, OF NORTH GRAFTON, MASSACHUSETTS, ASSIGNOR TO CROMPTON & KNOWLES LOOM WORKS, A CORPORATION OF MASSACHUSETTS.

LOOM.

No. 923,723.

Specification of Letters Patent.

Patented June 1, 1909.

Application filed January 19, 1906. Serial No. 296,779.

To all whom it may concern:

Be it known that I, HARRY W. SMITH, a resident of North Grafton, county of Worcester, State of Massachusetts, have invented 5 an Improvement in Looms, of which the following description, in connection with the accompanying drawing, is a specification, like numerals on the drawings representing like parts.

10 This invention relates to looms having shifting shuttle-boxes and has for its object to provide such looms with means for feeling the filling during the backward movement of the lay and just prior to the picking of the 15 active shuttle.

So far as I am aware, all looms which have any filling-detecting mechanism comprising a feeler to feel for the filling are so constructed that the feeling action of the feeler 20 takes place during the forward beat of the lay, and it is usually necessary to make this feeling action occur during a small increment in the movement of the lay. The result is that the feeling motion of the feeler is a 25 quick one, which is liable to injure delicate yarns. To avoid this objection, I have in my co-pending application Serial No. 293,911, Filed Dec. 30, 1905, described a loom having a feeler which is adapted to feel for 30 the filling during the backward movement of the lay so that more time may be given to the feeling movement of the feeler. The loom illustrated in said application is a single box loom, and in my present invention I have applied this type of feeler to a 35 drop box loom having shifting shuttle-boxes.

In accordance with my invention, I mount on the lay a feeler which moves with the lay, and I provide means for giving said feeler its 40 feeling movement during the backward movement of the lay, and just after the shuttle-boxes have shifted each shuttle-box is open at its side to admit the feeler, and the shifting of the shuttle-boxes brings that 45 box having the acting shuttle in opposite the feeler, so that when the feeler is given its feeling movement as the lay moves backwardly, said feeler enters the shuttle about to be thrown, and feels the filling therein.

50 The feeler mechanism may be used either to stop the loom when the filling in any shuttle is practically exhausted or it may be used to control a filling-replenishing mechanism which will replenish the filling.

55 I will now describe one embodiment of

my invention and then point out the novel features thereof in the claims.

In the drawings Figure 1 is a side view of a loom embodying my invention; Fig. 2 is a front view thereof; Fig. 3 is a side view looking in the opposite direction from Fig. 1, and Fig. 4 is a section through a shuttle, such as will be used in this embodiment of my invention, said figure showing the feeler in operation.

60 3 designates the frame of the loom, 4 the lay, 5 the lay swords and 21 the cam-shaft, and 7 the drop boxes having the shuttles 8 therein. These parts may be of any suitable or usual construction and form no part of 65 my present invention. Since my invention does not relate to the mechanism for operating or controlling the drop box, I have not deemed it necessary to illustrate such mechanism herein.

70 In this embodiment of my invention the feeler mechanism is illustrated as operating to control a filling-replenishing mechanism, and for the sake of illustration I have shown a filling-replenishing mechanism of the type 75 shown in patent to Wyman & Crompton No. 600,053. This filling-replenishing mechanism comprises a rotary hopper 6 containing a reverse supply of filling of different colors, 80 which is situated on the opposite side of the loom from the drop boxes, but is connected to the mechanism for operating said boxes, 85 so that the hopper moves in unison with the boxes.

90 I have not deemed it necessary to illustrate herein the entire mechanism for rotating the hopper, as this forms no part of my present invention.

95 The feeler is located on the same side of the loom as the shifting shuttle-boxes and each shuttle-box is open on its front side to admit the feeler during the feeling movement thereof.

100 The feeler is designated by 9 and it is here-
in shown as mounted on a slide or carriage 10 movably mounted on a bracket 11 carried by the lay. The feeler is adapted to move toward the shuttle to feel the filling therein, this feeling movement occurring during the backward movement of the lay. As stated above, any suitable mechanism may be employed for giving to the feeler its feeling movement provided such movement occurs during the backward movement of the lay.

105 The mechanism I have herein shown com- 110

prises a lever 13 pivoted to a bracket 14 carried by the lay and pivotally connected at one end to the slide 10, and at the other end to one end of a lever 15, which is pivoted to a bracket 17 carried by the lay. The lever 15 is connected by a link 19 with one end of a cam controlled lever 16 which is pivoted to a suitable bracket 18 carried by the loom-frame. This lever 16 bears at one end 10 against a cam 20 fast on the cam-shaft 21 and the lever is held against the cam by a suitable spring 22 which is secured at one end to said lever and at the other end to any suitable fixed support, which I have herein 15 shown. Said fixed support has a collar 23 loosely mounted on the cam shaft 21. The cam 20 is provided with a low portion 210 which is so positioned that it comes under the end of the lever 16 just as the lay is moving 20 backwardly subsequent to the pick which has driven the acting shuttle into one of the shifting shuttle-boxes. The cam 20 normally holds the parts in the full line position, Fig. 1, that is, with the feeler withdrawn 25 from the shuttle, but whenever the low portion 210 of the cam comes underneath the lever 16, the spring 22 operates through the levers above described to give the feeler its feeling movement toward the shuttle. Since 30 this feeling movement of the feeler is caused entirely by the spring 22, it will be observed that it is a yielding motion rather than a positive one.

The stop motion for the loom or the filling 35 replenishing mechanism, whichever is to be controlled by the feeler, is, in this embodiment of my invention, actuated by or set in motion by a bunter 26 carried by the lay and controlled as to its position by the feeler. 40 Normally the bunter occupies the inoperative position shown in full lines, Fig. 2, but when the feeler detects the practical exhaustion of the filling, said bunter is thrown into its operative position. The bunter is herein 45 shown as being pivoted to the lay as at 32 and as being provided with a tail 31 to which is pivotally connected a connector 30 slidably mounted in bearings 300 carried by the lay. This connector has at one end a head 50 29 adapted to engage one end of a controller 28 pivotally mounted on the feeler 9 as at 280. The other end of the controller is provided with a head 33 having an inclined surface 330 which co-operates with an inclined 55 surface 331 formed on one wall of the hole 332 on the side of the shuttle, through which the feeler 9 enters to feel the filling 333. The head 33 is preferably adjustably mounted in the controller, and so positioned that 60 the inclined surface thereof will not strike the inclined surface 331 of the shuttle, until the filling is substantially exhausted from the shuttle. With this arrangement of parts, it will be observed that so long as 65 there is any quantity of filling in the shuttle,

the inclined surface 330 of the head of the controller will not engage the corresponding inclined surface of the shuttle during the feeling movement of the feeler, and therefore the controller will normally retain the position shown in Fig. 4, in which position it is engaged by the connector. Whenever the filling is substantially exhausted, however, the feeler will, during its feeling movement enter the shuttle to an extent sufficient to 70 bring the head 33 against the inclined wall of the shuttle, thereby tilting the other end, and disconnecting it from the head 29 of the connector. When the connector is thus released, it will be moved to the right, Fig. 2, 80 through mechanism which will be described, thus throwing the bunter into operative position.

The means for shifting the connector after it is released, comprises a lever 38 pivoted 85 to one of the lay swords as at 39, and carrying a pin 42 which occupies a slot 40 of the connector, a spring 41 connecting the connector and said lever, and a cam 35 on the cam shaft 21 for oscillating said lever. This 90 cam 35 is shown as engaging one end of a lever 36 pivoted to the floor or to the frame of the loom as at 37 and also having a pivotal connection with the lever 38. Each rotation of the cam shaft will cause the lever 38 to 95 oscillate, but so long as the head of the connector engages the controller 28 such oscillation merely results in stretching the spring 41. As soon as the controller is released from the connector, however, as above described, said connector is free to move to the right, Fig. 2, and such movement will occur when the lever 38 is turned by the cam 35, the spring 41 serving as the connection between the lever 38 and the connector to 100 cause the latter to move with the lever. The lever 36 is normally held against the cam 35 by means of a spring 390.

The type of filling-replenishing mechanism herein illustrated is that which contains a 110 reserve supply of bobbins adapted to be inserted into a shuttle. These bobbins are thus transferred from the magazine 6 to the shuttle at the proper time by a transfer 115 24 to which is pivoted a dagger 25. When the bunter 26 is in its operative position, as is the case when the connector is in engagement with the controller, said bunter 25 does not engage the dagger upon the forward movement of the lay, and therefore the filling replenishing mechanism does not operate. As soon, however, as the filling in any shuttle 120 is substantially exhausted, and for this reason the controller releases the connector, the bunter 26 will be thrown into its operative position; in which position it strikes the dagger as the lay beats up, thus causing a fresh bobbin to be supplied to the shuttle in place of the exhausted bobbin. It would be 125 possible, however, to use my mechanism for 130

setting in motion loom stopping mechanism other than loom-replenishing mechanism. It will be noted that I employ one feeler only, and that the feeling movement of the feeler occurs during the backward movement of the lay just after the shuttle boxes have been shifted and just prior to the picking of the shuttle. The feeler therefore always feels for the filling in the shuttle which is about to be thrown; and if the filling in said shuttle is practically exhausted, the filling-replenishing mechanism is set in operation to replenish such exhausted filling when the shuttle reaches the opposite side of the lay. By performing the filling operation during the backward movement of the lay, it is possible to give more time to it so that the feeler may have a softer and more delicate touch and be less liable to injure the filling than if the movement of the feeler had to be a quick one, as is the case when the feeling is accomplished on the forward movement of the lay.

The mechanism herein illustrated is only one way of carrying out the desired results, and therefore I do not wish to be limited to the exact construction shown.

Having fully described my invention, what I claim as new and desire to secure by Letters Patent is:—

1. In a loom, a plurality of shifting shuttle-boxes, a feeler, and means to cause the feeler to feel for the filling in the active shuttle on the backward movement of the lay.
2. In a loom, a plurality of shifting shuttle-boxes, a single feeler, means to cause said feeler to feel for the filling in the shuttle about to be picked just prior to the time when said shuttle is picked.

3. In a loom, a plurality of shifting shuttle-boxes, filling-replenishing mechanism, means to cause detection of substantial exhaustion of the filling in the active shuttle subsequent to the shifting of the shuttle-boxes and during the backward movement of the lay.

4. In a loom, a lay, means to bring different kinds or colors of filling into play at predetermined intervals, a feeler carried by the lay, filling-replenishing mechanism controlled by the feeler, and means to cause the feeler to feel for the filling in the active shuttle during the backward movement of the lay.

5. In a loom having means to bring different kinds or colors of filling into play at predetermined intervals, filling-replenishing mechanism for supplying the different kinds or colors of filling, a single feeler controlling the operation of the filling-replenishing mechanism, and means to give the feeler its feeling movement during the backward movement of the lay.

In testimony whereof, I have signed my name to this specification, in the presence of two subscribing witnesses.

HARRY W. SMITH.
